UNITED STATES PATENT OFFICE.

JAMES KEYSER AND CHARLES ROCHE, OF SLIDELL, LOUISIANA.

COMBINED LEVEL AND PLUMB.

SPECIFICATION forming part of Letters Patent No. 628,334, dated July 4, 1899.

Application filed July 28, 1898. Serial No. 687,127. (No model.)

To all whom it may concern:

Be it known that we, JAMES KEYSER and CHARLES ROCHE, citizens of the United States, residing at Slidell, in the parish of St. Tammany and State of Louisiana, have invented new and useful Improvements in a Combined Level and Plumb, of which the following is a specification.

This invention relates to improvements in combined levels and plumbs in which neither spirit nor cord is employed; and it contemplates the construction of such a device at a comparatively small expense and one in which the parts are not liable to become injured or get out of order by exposure and rough usage.

The invention and its advantages will appear from the following description and claim when taken in connection with the annexed drawings, in which—

Figure 1 is a front view of our improved device. Fig. 2 is a sectional view taken in the plane indicated by the dotted line 2 2 on Fig. 1, and Fig. 3 is a perspective view of the needle or pendulum.

Referring by letter to said drawings, A indicates the body of our improved device. This body is of the size and form usually employed, and may be composed of wood or other suitable material having its edges planed true, and is provided centrally with a transverse opening *a*, which may be circular, and this opening is provided with two circular grooves or rabbets *b*, for a purpose which will presently appear.

B indicates two similar disks. These disks may be composed of sheet metal or other suitable material, having inwardly-directed annular portions *d* and laterally-disposed marginal flanges *e*. The portions *d* have marked upon their outer sides the degrees of a circle, and they are disposed to each other in a slightly-converging manner, as better shown in Fig. 2 of the drawings, so that their inner edges are closer together than their outer or flanged edges, and the flanges *e* are placed snugly in the circular recesses or rabbets *b* of the body A and are covered by crystals C, which are of circular form and are placed against the edges of the flanges *e* and also in the rabbets *b*. These crystals or transparent disks are held in position by means of rings D, which

are also placed in rabbets or recesses *f*, formed in the opposite outer faces of the body, and such rings, which are secured by screws or the like, extend sufficiently into the opening *a* to firmly engage and hold the disks or crystals, and consequently the dials, in a firm and substantial manner.

E indicates the needle or pendulum. This pendulum, as better shown in Fig. 3 of the drawings, has its lower end weighted or enlarged, as shown at *g*, and its upper or opposite end is forked, so as to provide two pointers *h*. These branches of the fork which form the pointers are here shown and in practice are preferably of a compound curvature, so that one may pass over the outside of each graduated disk, while the pendulum may remain suspended in the center of the opening *a*. By reason of the dials or graduated disks being arranged converging toward the center, as described, the weighted end of the pendulum may be enlarged toward its terminal and be permitted to swing freely between such dials and yet be made comparatively small. This pendulum is provided at a suitable point in its length with laterally-disposed studs or journals *i*, and the ends of such journals are tapered, so as to enter recesses *j*, cut or formed at diametrically opposite points in the inner sides of the crystals C. This construction permits of a bearing having but little friction. The parts are all so closely and snugly arranged as to exclude dust and moisture, which is an important desideratum, and yet should any of the parts become broken or injured they can be readily removed and replaced by others without the employment of skilled labor.

With a device of this construction it will be seen that we have all the advantages of both a plumb and a level without the disadvantages of either.

Having thus described our invention, what we claim is—

The improved level and plumb described consisting essentially of the body A having the central transverse opening *a* and the inner circular grooves or rabbets *b* and the outer grooves or rabbets *f* in the opposite sides of the body and surrounding the opening, the two disks B having the inwardly-directed, annular portions *d* arranged at an interval so

as to allow a space between them, and also having the laterally-disposed flanges *e* arranged in the rabbets *b*, the two crystals *C* placed against the lateral flanges of the disks *B*, the rings *D* securing the crystals and disks in position, and the pendulum *E* having the central journal with pointed ends and bearing in the crystals, said pendulum having its lower end weighted and arranged between the disks *B* and its opposite end forked and curved as shown so that one branch will pass

on the outer side of each disk, substantially as specified.

In testimony whereof we have hereunto set our hands in presence of two subscribing witnesses.

JAMES KEYSER.

CHARLES ROCHE.
